E. E. WANAMAKER

EXTENSION BED

Filed April 5, 1921

INVENTOR

Edmund E. Wanamaker

BY *Thomas L. Wilder*

ATTORNEY

UNITED STATES PATENT OFFICE.

EDMUND E. WANAMAKER, OF NEW HARTFORD, NEW YORK.

EXTENSION BED.

Application filed April 5, 1921. Serial No. 458,691.

To all whom it may concern:

Be it known that I, EDMUND E. WANAMAKER, a citizen of the United States, residing at New Hartford, in the county of Oneida and State of New York, have invented certain new and useful Improvements in Extension Beds, of which the following is a specification, reference being had therein to the accompanying drawing.

10 My invention relates to an extension bed and I declare the following to be a full, clear, concise and complete description thereof of sufficient to enable anyone skilled in the art to which it appertains to make and use 15 the same, reference being had to the accompanying drawings in which like reference characters refer to like parts throughout the specification.

The object of the invention is to provide 20 an elevating frame for an extension day bed, a couch or cot, which will be of simple construction and can be easily and quickly actuated into elevated position. To this end, the elevating frame embodies rock members 25 adapted to elevate the spring mattress carried thereon by swinging the pillow rest member of said frame into upright position.

The object will appear by referring to the drawings, in which:

30 Fig. 1 is a perspective view of an extension day bed, showing the parts in extended position; and auxiliary spring removed;

Fig. 2 is a detail perspective view of the elevating frame;

35 Fig. 3 is a detail fragmentary perspective view of an angle guide rail employed for sliding the extension frame on;

Fig. 4 is a detail perspective view of the extension spring used;

40 Fig. 5 is an enlarged perspective view of a fragment of the extension frame, showing the locking bolt attached at one end.

Referring more particularly to the drawings, an ordinary day bed, couch or cot bed 45 is represented by —1— having end members 2 and 3 and adapted to support a spring 4. The bed is provided also with guide ways formed by shoulder brackets 5, 5 mounted on each of the end members 2 and 3, whereby 50 to permit the extension frame 6 to slide under the spring 4 of the bed, when not needed. Any well known stop device for limiting the outward movement of the extension with reference to the bed —1— may be used such

as slide bolts 10, 10 disposed on either end 55 of the rear side of the extension frame 6 and adapted to engage shoulders 11, 11 formed integral with the shoulder brackets 5. The slide bolts 10 can be drawn free of the shoulders 11 when it is desired to remove the 60 extension frame 6 altogether from the bed frame —1—.

Within the extension frame 6, there is 65 mounted a novel rock frame 15, which comprises the two rock shafts 16, 16 that are journaled in bearings made by countersinking holes in the respective sides of the frame 6. Arms 17, 17 and 18, 18 are mounted in sets upon the rock shafts 16 and are fixed to turn with said shafts 16 by set screws 20. 70 Each of the arms 17 and 18 is formed with a curve therein, in order to avoid a dead center element in the rock of the frame 15, as well as to stabilize the frame when in upright position. Each of the arms 18 is 75 formed with an integral bracket 21 that is disposed substantially in parallel relation to the arm 18 and are adapted to support at their upper ends a cross piece 22 for a pillow rest.

The upper ends of the arms 17 and 18 are 80 connected by the two rods 24, 24 which unite in each instance an arm 17 and an arm 18. The rods 24 are made with their extreme ends bent at right angles which pass through suitable apertures in the upper ends of each of the arms 17 and 18 arranged in sets of two, as above stated and are riveted in place in such manner that the ends turn freely in the recesses formed in said arms 17 and 18, 85 whereby the frame 15 can be moved from its lower to upper position or vice versa, as illustrated by the full and dotted lines in Fig. 2. Rollers A are disposed in the recesses formed in arms 17 and 18 and are adapted 90 to rotate on the ends of rods 24, 24, whereby to aid in reducing friction. The rock frame 15 carries a demountable spring 30.

The operation of the rock frame 15 is 95 effected, after the extension frame 6 has been drawn out to its full extent, by manipulating the pillow rest 22, which is grasped and swung into upright position, thereby elevating the rock frame 15 to upper position in order to elevate the upper surface of the auxiliary or extension spring mattress 30 100 even with the upper surface of the main spring mattress 4 to form a bed. When fold-

ing the bed, the rock frame 15 is lowered by again swinging the pillow rest 22 into the dotted line position illustrated in Fig. 2 and then pushing the extension frame 6 under 5 the main bed 1.

It will be noted that to elevate or lower the rock frame 15, whereby to raise or lower the auxiliary spring 30, it is necessary only to manipulate the pillow rest 22. The auxiliary spring will raise and lower in the same 10 vertical plane because of the guide pins 31 fastened adjacent the four corners on the lower part of said auxiliary spring frame and adapted to ride in guide rings 32 secured 15 near the lower part of the extension frame 6.

The extension frame 6 is equipped with legs 33 to aid in supporting it, when in extended position.

Having thus described my invention what I claim as new and desire to secure by Letters Patent is:

In an extension bed, an extension frame supporting a spring mattress, rock shafts mounted on said extension frame, curved arms adapted to rock with said shafts, rods 25 connecting the upper ends of said arms, whereby said arms will move in the same direction to elevate and lower said mattress, and brackets supporting a cross piece, formed integral with certain of said arms, 30 whereby to aid in moving said arms in the same direction to elevate and lower said mattress.

In testimony whereof I have affixed my signature.

EDMUND E. WANAMAKER
